DESIGN FOR A PORTABLE BAR

Joseph R. Corbett, Sharonville, Ohio, assignor to Nu Tone Chimes, Inc., New York, N. Y., a corporation of New York

Application November 25, 1941, Serial No. 194,330

Term of patent 7 years

To all whom it may concern:

Be it known that I, Joseph R. Corbett, a citizen of the United States, residing at Sharonville, in the county of Hamilton and State of Ohio, have invented a new, original, and ornamental Design for a Portable Bar, of which the following is a specification, reference being had to the accompanying drawing, forming a part thereof.

I claim:

The ornamental design for a portable bar, substantially as shown.

JOSEPH R. CORBETT,
